[57] **CLAIM**

The ornamental design for a plate or similar article, as
shown and described.

DESCRIPTION

FIG. 1 is a top plan view of a plate or similar article of
conventional configuration showing my new design,
with a repeat unit being shown between the dashed
lines, it being understood that the design as shown
within the dashed line sector continues about the sur-
face of the plate along the indicated path;

FIG. 2 is a top plan view of a plate or similar article of
conventional configuration showing a modification of
my new design, with a repeat unit being shown between
the dashed lines, it being understood that the design as
shown within the dashed line sector continues about the
surface of the plate along the indicated path.
